(57) **CLAIM**

The ornamental design for a case for digital disks, as shown and described.

DESCRIPTION

FIG. 1 is a top plan view showing my new design for a case for digital disks,

FIG. 2 is a rear elevational view thereof,

FIG. 3 is a right side view, with the opposite side being a mirror image thereof,

FIG. 4 is a bottom plan view thereof,

FIG. 5 is a front elevational view thereof,

FIG. 6 is an outer perspective view of the case partially open, showing the transparent gloss outer plastic sheet separated from the main surfaces of the case,

FIG. 7 is an inside elevational view thereof shown in an open position;

FIG. 8 is a perspective view showing the gloss surfaces of the rib standing out with respect to the matte finish which covers the rest of the case,

FIG. 9 is an alternate embodiment of a top plan view showing my new design for a case for digital disks,

FIG. 10 is a rear elevational view of FIG. 9;

FIG. 11 is a right side elevational view of FIG. 9;

FIG. 12 is a bottom plan view of FIG. 9;

FIG. 13 is a front elevational view of FIG. 9;

FIG. 14 is an outer perspective view of FIG. 9 in a partially open position showing the transparent gloss outer plastic sheet separated from the main surfaces of the case;

FIG. 15 is an inside elevational view of FIG. 9 shown in an open position; and,

FIG. 16 is a perspective view showing the gloss surfaces of the rib standing out with respect to the matte finish which governs the rest of the case.
